SEWING MACHINE

Fred Ashworth, Wenham, Mass., assignor to
 United Shoe Machinery Corporation, Flemington, N. J., a corporation of New Jersey

Application November 29, 1944, Serial No. 565,586

4 Claims. (Cl. 112—62)

The present invention relates to improvements in moccasin seam sewing machines more particularly intended for operation on one-piece shoe uppers to insert a seam simulating one utilized to join together the top piece or tongue and the side piece or vamp of a moccasin-type shoe upper.

An example of a curved needle machine which may be employed satisfactorily to sew a moccasin seam joining together the top and side pieces of a shoe upper is disclosed in United States Letters Patent to the present inventor No. 1,975,914, granted October 9, 1934, and No. 2,221,320, granted November 12, 1940, having a work support provided with reentrant work engaging surfaces disposed at an angle to each other and extending in the direction of work feed. This type of machine also is employed advantageously to form a moccasin seam in a one-piece shoe upper.

Other moccasin-type seam sewing machines in commercial use are provided with two needles acting upon a one-piece shoe upper while being presented in flattened condition but, in order to insure that a ridge simulating a moccasin seam will be raised, a filler strip ordinarily is employed between the exposed threads of the seam, and a complex thread handling mechanism is required for connecting the threads inserted by the needles beneath the upper to bind the strip to the upper. The use of a filler strip also requires the application of additional guiding devices in the machine and increases the cost of operation.

When sewing a one-piece moccasin-type seam with a single curved needle machine such as disclosed in the inventor's patents above referred to, no substantial changes or additions to the machine are required, the upper being presented to the machine in such a way that a moccasin seam simulating ridge is raised automatically by the shape of the work supporting and clamping parts and retained by the tension of the stitches inserted.

In order to assist in guiding the formation of a moccasin seam in a one-piece shoe upper and to increase the resemblance between the one-piece seam and a two piece moccasin seam, it has heretofore been the practice to trace along the grain surface of a one-piece upper a line corresponding to the shape of the seam to be inserted. If, in tracing the guiding line for the seam, the grain layer of the upper is cut partially or wholly through, the seam while being inserted will draw together the parts of the upper at opposite sides of the slit so cut, giving the appearance of raw edges such as those presented in a two-piece moccasin-type upper.

The object of the present invention is to improve the construction and mode of operation of a single curved needle machine intended to sew a moccasin seam in a one-piece shoe upper in such a way that the necessity for cutting through the grain layer of the upper to simulate the raw edges of a two-piece moccasin seam in a separate operation before sewing is unnecessary so that a slit may be cut accurately and at a uniform depth through the grain layer of a one-piece shoe upper exactly intersecting the ridge raised in the material by the seam between the exposed stitches while the seam is being inserted.

The illustrated form of the machine constructed to attain this object comprises a work support having work engaging surfaces disposed with relation to each other and extending in the direction of work feed to form an angle, and an internal presser having similarly shaped work engaging tip surfaces complementary to those of the work support mounted to operate between the work engaging surfaces of the work support to form a moccasin seam simulating ridge, in which there is provided a knife, the cutting edge of which intersects the angle of the work support and enters the material of the upper being operated upon. By this construction a moccasin ridge may be raised and slit during sewing without the use of a filler strip or the attendant expense of construction and materials. In its preferred form, the presser tip has a projection acting to compress the material of the upper and to crowd it into the angle of the work support opposite the sewing point, and the work slitting knife acts opposite the projection upon the compressed material of the upper to insure formation of the slit at a uniform depth. Also, according to this feature of the invention, the depth of the slit beneath the grain surface of the upper material is limited by gaging means acting adjacent to the cutting edge of the knife.

These and other features of the invention are embodied in the devices, combinations and arrangements of parts hereinafter described and claimed, the advantages of which will be readily understood from the following description taken in connection with the accompanying drawing, in which

Fig. 1 is a view in side elevation, looking from the right, surrounding the point of operation of portions of a sewing machine in which the features of the present invention are embodied;

Fig. 2 is a plan view on an enlarged scale of the work support of the machine of Fig. 1, partly

broken away and illustrating the cutting action of the slitting knife; and

Fig. 3 is a perspective view of the toe portion of a shoe comprising a one-piece upper in which a slit moccasin-type seam is inserted.

The machine illustrated in Figs. 1 and 2 in its construction and mode of operation is similar to that of Patent No. 1,975,914 above referred to and is primarily intended to operate on bevel-edged moccasin parts including a top-piece or tongue and a vamp or side piece of a shoe upper, previously assembled with cement as a temporary connecting agent. The machine also is well adapted for use in sewing a moccasin seam in a one-piece shoe upper such as that indicated in Fig. 3 of the drawing at 2 to raise a U-shaped ridge 10 about the toe of the shoe both for ornamental as well as structural reinforcing purposes. During sewing, the seam 4 having exposed portions of the threads maintains an angular shape in the material of the upper as formed by the co-operative action of a work support 6 and a presser 8 in the machine and draws the sides of the angle together at its apex to produce a peak on the ridge. The upper 2, after sewing the moccasin seam, is lasted in the usual way and attached to a sole member 12 to complete the shoe.

The illustrated machine is provided with a curved hook needle 14 and a curved work penetrating and feeding awl 16 acting to enter and emerge from the same side of the work, a horn 18 and other lockstitch forming devices of the usual form. The work is fed through the machine by the movement of the awl while engaging the work toward a position of alignment with the needle so that the needle will enter the perforation formed by the awl. When the awl withdraws from the work, it is backfed the length of a stitch and again penetrates the work.

The upper is clamped in position during formation of each stitch between the work support 6 and the presser 8 which is secured to the end of the horn. The co-operating work engaging surfaces of the work support and presser extend in the direction of feed, are complementary and are disposed in angular relation. The work support is formed in two parts with a reentrant angle between the parts, one of which is already designated by the numeral 6 and the other of which, indicated at 20, is secured to the part 6 by a pair of spaced screws 22, one or more vertical dowels 24 passing through the parts for maintaining the proper alignment. A continuation of the line of division between the parts 6 and 20 of the work support intersects the angle formed by the reentrant work engaging surfaces thereof.

Besides having external angularly disposed work engaging surfaces of the same angle as the co-operating surfaces of the work support, the presser tip has a projection 26 located along the line of the seam between the work penetrating positions of the needle and awl substantially opposite the sewing point, the presser tip being cut away to provide a clearance recess for the needle and awl at either side of the projection. The purpose of the projection 26 is to crowd the material of the upper firmly into the apex of the angle formed by the internal work engaging surfaces of the work support so that the seam 4 will be inserted with uniform spacing of the exposed threads in the stitches along the outer grain surface of the upper. The action of the stitches while drawing the inner sides of the material in the upper together and retaining the material permanently in this relationship avoids the necessity for in-

serting a filler strip to form the ridge 10 as with two-needle machines.

While inserting the seam according to the present invention, a slit 27 entering the grain layer

5 of the upper material at exactly the center of the ridge 10 between the exposed threads in the seam is cut by a flat sheet-metal knife 28 disposed with its cutting edge intersecting the angle of the work engaging surfaces on the work support 6, 20. 10 To secure the knife 28 in place, it is constructed in the form of a plate and located between the parts 6 and 20 of the work support, having perforations to receive the screws 22 and the dowels 24.

15 In order to reinforce the cutting edge of the knife and to limit the depth of the slit cut thereby, a pair of spacing plates 30 are arranged one on either side of the knife with forwardly facing gaging edges extending outwardly from the apex 20 of the angle of the work support sufficiently to enable the folded-over material of the upper to bear against the plates. Thus, it is impossible to thrust the upper during formation of the ridge 10 against the knife to increase the depth of the slit.

25 The cutting edge of the knife is provided by sharpening one edge of a lip 32 extending from the knife opposite the work compressing projection 26 of the presser tip 8. With this arrangement a constant and uniform compression of the material in the upper while being acted upon by the knife is insured. With variations in thickness of the upper material, the presser tip 8 will be held farther away from the knife or allowed to approach closer thereto while maintaining uniform compression of the material against the knife at all times. The location of the lip 32 opposite the projection 26 is of further advantage in that, during tipping and turning movements of the upper in presenting it to the machine, there is no tendency for the curved portions of the seam to carry the ridge 10 farther away from or closer to the cutting edge which is opposite the sewing point in the machine.

30 The nature and scope of the invention having been indicated and a construction embodying the invention having been specifically described, what is claimed is:

1. In a machine for sewing a moccasin seam in a one-piece shoe upper, having a work support 50 provided with work engaging surfaces disposed with relation to each other and extending in the direction of work feed to form an angle and stitch forming devices comprising a single curved needle movable across the angle of said surfaces to enter and emerge from the same side of the work supported by the work support and an internal presser having a tip with work engaging surfaces disposed at the same angle as that of the work engaging surfaces of the work support, in combination with a work engaging knife intersecting 55 the angle between the work engaging surfaces of the work support and entering the material of the upper being operated upon between the exposed threads of a seam inserted by the stitch forming devices to form a slit along a ridge raised by the seam inserted by the stitch forming devices.

2. In a machine for sewing a moccasin seam in a one-piece shoe upper, having a work support 60 provided with work engaging surfaces disposed with relation to each other and extending in the direction of work feed to form an angle, stitch forming devices comprising a curved hook needle movable across the angle of said surfaces to enter and emerge from the same side of the work supported by the work support and an internal 65

presser having a tip with work engaging surfaces disposed at the same angle as that of the work engaging surfaces of the work support, and a projection on the presser tip acting to compress the material of the upper and crowd it into the angle of the work support, in combination with a work engaging knife arranged with its sharpened edge opposite the projection of the presser tip intersecting the angle between the work engaging surfaces of the work support to cut a slit along a ridge raised in the material by the seam inserted by the stitch forming devices.

3. In a machine for sewing a moccasin seam in a one-piece shoe upper, having a two-part work support provided with work engaging surfaces disposed with relation to each other and extending in the direction of work feed to form an angle, the line of division between the parts of the work support intersecting the angle of the work engaging surfaces, stitch forming devices comprising a curved hook needle movable across the angle of said surfaces, and an internal presser having a tip with work engaging surfaces disposed at the same angle as that of the work engaging surfaces of the work support, in combination with a flat knife clamped along its flat sides between the parts of the work support and arranged with its

cutting edge entering the material of the upper being operated upon between the exposed threads of the seam inserted by the stitch forming devices to form a slit along a ridge raised by the seam.

- 5 4. In a machine for sewing a moccasin seam in a one-piece shoe upper, having a two-part work support provided with work engaging surfaces disposed with relation to each other and extending in the direction of work feed to form an angle, the line of division between the parts of the work support intersecting the angle of the work engaging surfaces, stitch forming devices comprising a curved hook needle movable across the angle of said surfaces, and an internal presser having a tip with work engaging surfaces disposed at the same angle as that of the work engaging surfaces of the work support, in combination with a flat knife clamped between the parts of the work support and arranged with its cutting edge entering the material of the upper being operated upon between the exposed threads of the seam inserted by the stitch forming devices to form a slit along a ridge raised by the seam, and gaging means acting adjacent to the cutting edge of the knife to limit the depth of the slit cut by the knife.
